CARL GUSTAF SWEBILIUS AND HANS T. R. HANITZ, OF NEW HAVEN, CONNECTICUT,
ASSIGNORS TO THE MARLIN FIREARMS COMPANY, OF NEW HAVEN, CONNECTICUT,
A CORPORATION OF CONNECTICUT.

FIREARM.

1,157,656.

Specification of Letters Patent. Patented Oct. 19, 1915.

Application filed July 29, 1915. Serial No. 42,471.

To all whom it may concern:

Be it known that we, CARL G. SWEBILIUS and HANS T. R. HANITZ, a citizen of the United States of America and a subject of the Emperor of Germany, respectively, both residing at New Haven, New Haven county, Connecticut, have invented a new and useful Firearm, of which the following is a specification.

10 Our invention relates to firearms, and particularly to rifles of the single shot variety.

The invention consists in a new and useful cartridge extracting and ejecting means which is designed to reliably and effectively 15 dislodge and eject an empty shell from the chamber of the barrel.

In the drawings: Figure 1 is a side elevation, partly in section, of the middle or breech portion of a firearm equipped with 20 our invention. Fig. 2 is a similar view showing the parts in a different position. Fig. 3 is also a similar view showing the parts in still another position. Fig. 4 is a section on the line 4—4 of Fig. 1. Fig. 5 is a front elevation of certain parts detached. Figs. 6, 7 and 8 are perspective views of details.

1 represents the receiver, 2 the stock, 3 the barrel, 4 the breechblock, 5 the breechblock operating lever, 6 the hammer pivoted to and carried by the breechblock 4, and 7 the trigger, likewise pivoted to and carried by the breech block. The lever 5 is pivoted to the underside of the receiver frame 1 on the pivot pin 8. 9 is an extension at the 35 pivoted end of the lever which is connected to the breech block through the medium of a link 10.

11 is the usual firing pin carried by the breechblock for operation by the hammer 6. 40 12 is a pin carried by the frame and upon which the rear end of the breechblock 4 is mounted to slide and partially turn as said breechblock is moved up and down. The rear end of the breechblock may be slotted 45 as shown, to receive the pin 12.

13 is a locking shoulder or abutment on the receiver against which a shoulder 14 on the breech block may abut when the breech block is locked up, and the gun is ready for 50 firing, as shown in Fig. 1, in which position, said breechblock will be solidly held between said abutment, the rear end of the barrel, and the lever pivot 8.

Our improved extractor and ejector com-

prises an upright arm 15 which is pivotally supported at its lower end, for example on the pin 8, the upper end of the arm 15 carrying a lateral offset 16 which directly engages the rim of the cartridge as it stands in the barrel, so that when the arm 15 is swung back, the cartridge will be extracted and ejected. This extractor is located in a recess or space between the side wall of the breech block and the adjacent side wall of the receiver. At the forward edge of the arm 15, and toward the lower end thereof is a projection 17 which provides two opposite inclines, as shown, which are designed to co-operate with a spring plunger 18 which is mounted in the front end of the receiver, 70 and is pressed by a spring 19 in a direction to cause the plunger 18 to yieldingly bear against one side or the other of the projection 17. 75 One edge of this projection 20 is partially beveled, as indicated at 21. This projection 20 coacts with another spring plunger 22 arranged to project from the side of the breech block 4. The projecting end of the 80 spring plunger 22 is likewise partially beveled on that side which faces the incline 21 on the extractor. 23 is a lug on the side of the upper part of the breech block 4 which is also designed to co-operate with the extractor in the manner and for the purpose described hereafter.

Operation: Let it be assumed that the parts stand in the position shown in Fig. 1, wherein the gun is locked up ready for 90 firing. When the hammer has dropped and the gun has been fired, the operator may swing the lever 5 downwardly so as to lower the breech block. When the breech block has been lowered to a sufficient extent to 95 clear the empty shell in the chamber of the barrel,—that position being approximately indicated in Fig. 2,—the plunger 22 will encounter the end of the projection 20 on the extractor, so that the further descent of the 100 breech block will cause the extractor to tilt backwardly on its pivot 8, thus extracting the shell. This first partial movement of the extractor is comparatively slow. When, however, the extractor has tilted sufficiently 105 to cause the point 17 to clear the point 18^a of the plunger 18, the spring 19 will cause the plunger 18 to jump ahead quickly so as

to impart a very quick backward throw to the extractor, thus guaranteeing the certain ejection of the empty shell. The extreme rearward movement or position of the extractor is indicated in dotted lines, Fig. 2. The continued forward swinging movement of the lever 5 from the position indicated in Fig. 2 to that indicated in Fig. 3 imparts, in effect, a downward and forward movement to the upper end of the breech block, whereby the lug 23 on the latter engages the rear edge of the extractor, and swings it ahead again to the position indicated in Fig. 3, on which movement the plunger 22 is repressed by the cam incline 21, so as to permit the breech block to descend, while the extension 20 is ascending. At this time also, the projection 17 at the forward edge of the extractor snaps down from the upper 10 side of the plunger 18 to the lower side, as indicated in the several views. The gun may now be reloaded, whereupon the lever 5 may be swung back from the position indicated in Fig. 3 to that indicated in Fig. 1, thus completing a cycle of operations.

The effect of the plunger 18 against the opposite inclines of the projection 17 is to hasten the last part of the rearward movement of the extractor for the above purpose, and to also hasten the last part of the forward movement thereof so as to guarantee the seating of the offset end 16 in its inactive position.

What we claim is:

35 1. In a single shot firearm, a receiver, a barrel having a cartridge chamber at its rear, a combined extractor and ejector arranged adjacent thereto, a breech block movable in said receiver into and out of position relatively to the rear of said barrel and chamber to open and close the latter, with means moved by the breech block on its opening movement to both retract said extractor and to then advance the same to its inactive position.

40 2. In a single shot firearm, a receiver, a barrel having a cartridge chamber at its rear, a combined extractor and ejector arranged adjacent thereto, a breech block movable in said receiver into and out of position relatively to the rear of said barrel and chamber to open and close the latter, with means moved by the breech block on its opening movement to both retract said extractor and to then advance the same to its inactive position, said means being carried by the breech block.

45 3. In a single shot firearm, a receiver, a barrel having a cartridge chamber at its rear, a combined extractor and ejector arranged adjacent thereto, a breech block movable in said receiver into and out of position relatively to the rear of said barrel and chamber to open and close the latter, with means operable upon the opening movement

of the breech block to both retract said extractor and to then advance the same to its inactive position, said means being carried by the breech block and comprising a spring stud, and a lug.

4. In a single shot firearm, a receiver, a barrel having a cartridge chamber at its rear, a combined extractor and ejector arranged adjacent thereto, a breech block movable in said receiver into and out of position relatively to the rear of said barrel and chamber to open and close the latter, with means operable upon the opening movement of the breech block to both retract said extractor and to then advance the same to its inactive position, with means for accelerating the last part of the rearward movement of the extractor to speedily eject a shell.

5. In a single shot firearm, a receiver, a barrel having a cartridge chamber at its rear, a combined extractor and ejector arranged adjacent thereto, a breech block movable in said receiver into and out of position relatively to the rear of said barrel and chamber to open and close the latter, with means operable upon the opening movement of the breech block to both retract said extractor and to then advance the same to its inactive position, said means being carried by the breech block and comprising a spring stud, and a lug, with means for hastening the last part of the rearward movement of the extractor to speedily eject a shell, said means operating to hasten the last part of the forward movement of said extractor to force it fully into and hold it in its inactive position.

6. In a single shot firearm, a receiver, a barrel having a cartridge chamber at its rear, a combined extractor and ejector arranged adjacent thereto, a breech block movable in said receiver into and out of position relatively to the rear of said barrel and chamber to open and close the latter, with means operable upon the opening movement of the breech block to both retract said extractor and to then advance the same to its inactive position, said means being carried by the breech block and comprising a spring stud, and a lug, with means for hastening the last part of the rearward movement of the extractor to speedily eject a shell, said means operating to hasten the last part of the forward movement of said extractor to force it fully into and hold it in its inactive position, said means comprising a spring pressed plunger carried by the receiver and co-operating with said extractor.

7. In a single shot firearm, a receiver, a barrel carried thereby, a breech block movable up and down into and out of its operative position in the rear of the barrel, an extractor arranged between the side of the breech block and the adjacent

side of the receiver, said extractor being pivotally mounted at its lower end, means carried by the breech block to swing said extractor first backwardly and then 5 forwardly by the descending movement of the breech block.

8. In a single shot firearm, a receiver, a barrel carried thereby, a breech block movable up and down into and out of its operative position in the rear of the barrel, an extractor arranged between the side of the breech block and the adjacent side of the receiver, said extractor being pivotally mounted at its lower end, means carried by 10 the breech block to swing said extractor first backwardly and then forwardly by the descending movement of the breech block, comprising a spring detent projecting from the side of the breech block and operating with the extractor near its lower end, and a lug carried by the breech block 15 and coacting with the extractor above the point of engagement of said detent therewith.

9. In a single shot firearm, a receiver, a barrel carried thereby, a breech block movable up and down into and out of its operative position in the rear of the barrel, an extractor arranged between the side of the breech block and the adjacent side of the receiver, said extractor being pivotally mounted at its lower end, means carried by the breech block to swing said extractor first backwardly and then forwardly by the descending movement of the breech block, 25 comprising a spring detent projecting from the side of the breech block and co-operating with the extractor near its lower end, and a lug carried by the breech block and coacting with the extractor above the point of engagement of said detent therewith, and means carried by the receiver for hastening the last part of the rearward movement of the extractor and the last part of the forward movement thereof. 30 35 40
